Application May 1, 1930, Serial No. 448,839
Renewed February 2, 1932

9 Claims. (Cl. 250—27)

This invention relates to direct coupled cascaded electron tube systems, and more particularly to improvements in the direct coupled electron tube systems disclosed in my copending application Serial Number 381,754, filed July 29, 1929.

An object of my invention is the attainment of either the detection of high frequency modulated currents or substantially linear with frequency 10 amplification of audio frequency currents within one direct coupled tube system without change in the constants of the circuits when changing from a source of one type of signal to the other.

Another object of my invention is the alternating current energization of such a direct-coupled tube system with hum in the output of the system reduced to a minimum.

Further objects of my invention will become apparent as the description of my invention as 20 diagrammatically illustrated in the accompanying drawing is developed.

For the sake of simplicity and definiteness I shall give the constants of my improved circuit arrangement, but it is to be understood that these 25 constants may be varied to adapt the same to use with various tubes without departing from the spirit of my invention.

Referring to the drawing RT designates a 30 full-wave rectifier tube of the —80 type energized from a source of 110 volt alternating current AC through a power transformer PT, the rectifier delivering a potential of about 425 volts between the positive terminal P and the negative or grounded terminal G.

In shunt to the terminals P and G of the rectifier I have provided a filter system including filter condensers FC₁ and FC₂ of 1.0 microfarad capacity each, between which is located a filter choke coil FC_h having an inductance of about 40 20 henries.

In series with the filter choke coil FC_h between the terminals P and G of the rectifier I have connected the primary of an output transformer OT, the secondary of which is connected to the voice coil of an electrodynamic loud speaker LS, a radio frequency choke coil RFCh, the plate to cathode path of tube VT₂, a type —45 output tube, the filament of which is energized by a filament heating transformer HT₂ center-tapped as shown at CT₂ and a resistance R of about 6100 ohms. Between the filter choke coil FC_h and the center tap CT₂ I have connected two non-inductive series resistances R' and R'' having a value of about 100,000 and 25,000 ohms respectively.

The tube VT₁ of the —24 type includes a cathode which is energized from a heating current transformer HT₁ the secondary of which is connected to the point A on the resistance R of a value of about 425 ohms from the terminal G of the rectifier. The cathode proper is connected to the terminal G through a non-inductive stabilizing resistance SR of about 50,000 ohms.

The screen grid of tube VT₁ is connected to the point B on the resistance R of a value of about 1400 ohms from the terminal G. The plate of tube VT₁ is connected directly by a unipotential connection to the grid of tube VT₂ and to the point between the resistances R', R'' through a non-inductive resistance CR of a value of about 1/2 megohm.

The grid of tube VT₁ is connected through a phonograph pick-up or similar device with a shorting switch SW and a tunable circuit including a secondary S and tuning condenser TC to the point A on the resistance R, a signal current path being provided to the cathode through a signal current condenser SC₁ of a value of 1.0 microfarads.

The resistance R is shunted with a condenser RC of a value of 1.0 microfarads capacity, to bypass signal currents in the resistance R and a condenser SC₂ of 1.0 microfarads capacity is provided across the resistances R' and R'' to complete the signal current output circuit of tube VT₂, high frequency currents being shunted out of the output circuit by means of the condenser RFC of about 0.0005 microfarad capacity connected between the plate and center-tap CT₂ of tube VT₂.

Hum within the system is controlled by developing hum current potentials in the stabilizing resistance SR by means of the condenser HBC of 1.0 microfarads capacity connected to the variable tap D on the resistance R.

The operation of this system is as follows. When the constants hereinbefore set forth are used the space current of tube VT₂ is approximately 30 milliamperes and the plate current of tube VT₁ about 225 microamperes.

The stabilization features of this circuit are fully described in my copending application hereinbefore referred to and are briefly summarized here as follows. The bias for the whole system is determined by the differential voltage between the cathode of tube VT₁ and the point A on the resistance R which differential voltage is determined by the voltages produced by the space current of tube VT₁ flowing through the resistance 110

SR and the space current of the tube VT₂ flowing through the resistance R.

Should the voltage of the source AC fluctuate even through wide limits of 15 or more volts higher or lower than the rated 110 volts there is produced a change in the plate current of tube VT₂, which change in space current changes the potential of the point A with respect to ground and with respect to the cathode of tube VT₁ so that the grid of tube VT₁ becomes more positive or negative with respect to the cathode thereof causing more or less space current to flow through the tube VT₁. This change in space current flowing through the resistance CR automatically adjusts the bias of the grid of tube VT₂ to compensate for this change.

If the introduction of signal current potentials at PU or S causes a change in the average bias of the grid of tube VT₁ causing a change in the average space current thereof this is reflected into the space current of tube VT₂ which in turn re-establishes the potential of the point A with respect to the cathode of tube VT₁ compensating for the change therein caused by the introduction of signal current potentials at PU or S.

While I have described my invention as embodied in an apparatus having a particular set of constants with relation to certain commercially available tubes it is to be understood that variations in these constants are to be construed as coming within the scope of the claims appended hereto.

Having thus described my invention, what I claim is:

35. 1. In a direct coupled tube system, the combination of a rectifier and filter system comprising a source of unidirectional pulsating current; an output tube; a resistance, the anode to cathode path of said tube and said resistance being series connected across the terminals of said source; a pair of resistances connected between one terminal of said source and the cathode of said output tube; a four element tube; a stabilizing resistance series connected between the cathode of said four element tube and the other terminal of said source; connections between the grid and screen-grid of said four element tube and points of successively higher potential on said first mentioned resistance with respect to the negative terminal of said source; a unipotential connection between the anode of said four element tube and the grid of said output tube; and a coupling resistance connected between said unipotential connection and the point between said pair of resistances.

50. 2. In a direct coupled tube system, the combination of a rectifier and filter system comprising a source of unidirectional pulsating current; an output tube; a resistance, the anode to cathode path of said tube and said resistance being series connected across the terminals of said source; a pair of resistances connected between one terminal of said source and the cathode of said output tube; a four element tube including a screen grid; a stabilizing resistance series connected between the cathode of said four element tube and the other terminal of said source; a hum bucking condenser connected between the cathode of said four element tube and a tap on said first mentioned resistance; connections between the grid and screen-grid of said four element tube and points of successively higher potential on said first mentioned resistance with respect to the negative terminal of said source; a unipotential connection between the anode of said four element tube and the grid of said output tube; and

a coupling resistance connected between said unipotential connection and the point between said pair of resistances.

3. In a direct coupled tube system, the combination of a rectifier and filter system comprising a source of unidirectional pulsating current; an output tube; a resistance; a high frequency choke coil; said high frequency choke coil, the anode to cathode path of said tube and said resistance being series connected across the terminals of said source; a condenser of low impedance to high frequency current and high impedance to low frequency currents connected in shunt to the anode to cathode path of said output tube; a pair of resistances connected between one terminal of said source and the cathode of said output tube; a four element tube; a stabilizing resistance series connected between the cathode of said four element tube and the other terminal of said source; connections between the grid and screen-grid of said four element tube and points of successively higher potential on said first mentioned resistance with respect to the negative terminal of said source, a unipotential connection between the anode of said four element tube and the grid of said output tube and a coupling resistance connected between said unipotential connection and the point between said pair of resistances.

4. In a direct coupled tube system the combination of a rectifier and filter system comprising a source of unidirectional pulsating current; an output tube; a resistance; a condenser in shunt to said resistance; the anode to cathode path of said tube and said resistance being series connected across the terminals of said source; a pair of resistances connected between one terminal of said source and the cathode of said output tube; a four element tube; a stabilizing resistance series connected between the cathode of said four element tube and the other terminal of said source; connections between the grid and screen-grid of said four element tube and points of successively higher potential on said first mentioned resistance with respect to the negative terminal of said source, a unipotential connection between the anode of said four element tube and the grid of said output tube and a coupling resistance connected between said unipotential connection and the point between said pair of resistances.

5. In a direct coupled tube system the combination of a rectifier and filter system comprising a source of unidirectional pulsating current; an output tube; a resistance; the anode to cathode path of said tube and said resistance being series connected across the terminals of said source; a pair of resistances connected between one terminal of said source and the cathode of said output tube; a condenser in shunt to said pair of resistances; a four element tube; a stabilizing resistance series connected between the cathode of said four element tube and the other terminal of said source; connections between the grid and screen-grid of said four element tube and points of successively higher potential on said first mentioned resistance with respect to the negative terminal of said source, a unipotential connection between the anode of said four element tube and the grid of said output tube and a coupling resistance connected between said unipotential connection and the point between said pair of resistances.

6. In a direct coupled tube system the combination of a rectifier and filter system comprising a source of unidirectional pulsating current; an output tube; a resistance; the anode to cathode

- path of said tube and said resistance being series connected across the terminals of said source; a condenser in shunt to said resistance; a pair of resistances connected between one terminal of 5 said source and the cathode of said output tube; a condenser in shunt to said pair of resistances; a four element tube; a stabilizing resistance series connected between the cathode of said four element tube and the other terminal of said source; 10 connections between the grid and screen-grid of said four element tube and points of successively higher potential on said first mentioned resistance with respect to the negative terminal of said source, a unipotential connection between 15 the anode of said four element tube and the grid of said output tube and a coupling resistance connected between said unipotential connection and the point between said pair of resistances.
7. In a direct coupled tube system the combination of a rectifier and filter system comprising a source of unidirectional pulsating current; an output tube; a resistance; the anode to cathode path of said tube and said resistance being series connected across the terminals of said source; a 20 condenser in shunt to said resistance; a pair of resistances connected between one terminal of said source and the cathode of said output tube; a condenser in shunt to said pair of resistances; a four element tube; a stabilizing resistance series 25 connected between the cathode of said four element tube and the other terminal of said source; hum bucking condenser connected between the cathode of said four element tube and a variable tap on said first mentioned resistance; connections between the grid and screen-grid of said four element tube and points of successively higher potential on said first mentioned resistance with respect to the negative terminal of said source, a unipotential connection between the anode of said four element tube and the grid of 30 said output tube and a coupling resistance connected between said unipotential connection and the point between said pair of resistances.
8. In a direct coupled tube system the combination of a rectifier and filter system comprising a source of unidirectional pulsating current; an 35 condenser between the grid and screen-grid of said four element tube and points of successively higher potential on said first mentioned resistance with respect to the negative terminal of said source, a unipotential connection between the anode of said four element tube and the grid of 40 said output tube and a coupling resistance connected between said unipotential connection and the point between said pair of resistances.
9. In a direct coupled electron tube system, the combination of a tube having an output circuit 45 including a low frequency output impedance element, a radio frequency choke coil connected between the anode of said tube and said impedance element, a condenser of low impedance to high frequency currents and high impedance to low frequency currents connected between the anode and cathode of said tube in parallel to said radio frequency choke coil, a second tube having means for impressing on the input electrodes thereof high frequency currents modulated at low frequency, and means for transferring the current energy from said second tube to said first tube including a unipotential connection between the anode of said second tube and the control electrode of said first tube.
